UNITED STATES PATENT OFFICE.

RALPH W. CRARY, OF STURGEON BAY, WISCONSIN, AND ORANGE E. MCMEANS, OF INDIANAPOLIS, INDIANA.

TIME AND WAGE COMPUTER.

981,066.

Specification of Letters Patent. Patented Jan. 10, 1911.

Application filed December 16, 1909. Serial No. 533,438.

To all whom it may concern:

Be it known that we, RALPH W. CRARY, a citizen of the United States, residing at Sturgeon Bay, in the county of Door and 5 State of Wisconsin, and ORANGE E. MCMEANS, a citizen of the United States, residing at Woodruff Place, Indianapolis, in the county of Marion and State of Indiana have invented certain new and useful Improvements in Time and Wage Computers, 10 of which the following is a specification.

In the production of canned goods the work of a large number of laborers is required and these laborers are engaged in 15 various shifts or groups throughout the entire twenty-four hours of each day during the packing season and the individual laborers are apt to be quite irregular in the time of employment. As a consequence the laborers are in most instances paid by the hour at 20 various rates depending upon the character of labor and some means needs to be provided by which the actual time of employment and the character of employment may 25 be readily indicated and thereafter computed and reduced into terms of either hours or wage.

The object of our invention is, therefore, to produce means by which the above stated 30 results may be readily reached and to that end we have provided a peculiar time card to be given to each employee each twenty-four hours, and a computing or integrating scale by means of which each of the time 35 cards may, when properly marked, be clearly reduced into terms of either hours or wage.

While the above recited means has been especially designed for use by canners and packers it is to be understood that with very 40 slight changes not requiring invention, the means may be readily adapted for use in many other lines of employment.

The accompanying drawings illustrate our invention.

45 Figure 1 is a face view of the time card constructed and arranged in accordance with our invention and Fig. 2 a face view of a computing scale (preferably transparent) by means of which indications on a 50 time card such as shown in Fig. 1, may be reduced to terms of hours (and fractions thereof) or wage.

Referring to Fig. 1 of the drawings, the time card shown therein may be of any desired size and shape and should be provided

with a space A to receive the name of the employee and a space B to receive the designating number of the employee. It is convenient and desirable also to have a space C in which the date may be placed and spaces D, E, and F in which may be written a total time of employment in the morning, afternoon and the whole day respectively. In a space G we arrange a list of designations of the different classes of employment 65 and in a space H a list of rates per hour. We also provide two series of uniform spaces I beginning at 1 and ending at 1 passing through 12, so as to thus indicate the hours beginning at 1 a. m. and 2 p. m.; identical 70 uniform spaces and a series of J, beginning at 12 and ending at 12 passing through 1, said figures thus designating the hours from 12 noon until 1 o'clock a. m. Arranged alongside of the spaces I and J are equal 75 spaces K of any desired but equal extent so as to indicate equal sub-divisions of an hour. In the present case these sub-divisions are quarter hours, nothing less than 15 minutes being counted, and care should be exercised 80 to see that the subdivisions K are uniform throughout.

In the present instance we show the card provided with two series of spaces I and J for the following reason. If a single series 85 of twenty-four spaces I and a corresponding series of one hundred and eight spaces K were arranged in a straight line the card would be too long for convenient handling if the spaces K were of sufficient size to 90 facilitate easy handling, and it is therefore advisable to divide the set or entire number of spaces into two series. In the particular industry for which this card was especially designed the usual lunch period extends 95 from twelve to two o'clock, different employees taking their noonies at different times, and it was found convenient to get all of the time of any employee before lunch or after lunch into a single record. It is for 100 this reason that the series of spaces I is arranged to take care of the time from midnight until two p. m. and the series of spaces J is arranged to take care of the time from twelve noon until one o'clock a. m., thus providing each series of spaces with the entire noon period.

For the purpose of reducing the record of a card to terms of hours or wages we provide the scale shown in Fig. 2. This scale 110

may be made of any suitable material but we prefer to make it of a strip L of transparent material preferably flexible such as celluloid. On this scale we provide a series 5 of twenty-five spaces M having the same length as spaces I and J and alongside this series is a series of spaces N corresponding in extent to the series K. We then provide a plurality of series of columns of spaces P 10 each representing a wage scale. The spaces in any column P correspond to the spaces in column N and each space will contain that figure which will represent the total wage for the indicated time at the indicated wage 15 scale.

In use an employee is given one of the cards shown in Fig. 1 at time of beginning 20 of work on any day and a punch or other designating mark will be made in that space K which will designate the actual time of beginning of work. When the employee stops for lunch another indication will be placed in the proper space K alongside of the column I and when the employee begins 25 after lunch a proper designating mark will be placed in the proper space K alongside of column J and a similar mark made to indicate the time of quitting at the end of the day. A proper designating mark will 30 also be made in column G to indicate the kind of employment and a mark in column H to indicate the wage scale. Each employee will turn in his or her card at the end of employment for the day (or night) 35 and the auditor will then take the scale L and, by using the proper column P, and placing the "0" of the wage scale column at the mark indicating the time of beginning, will note the reading indicated by the 40 mark of lunch quitting and will then transfer the scale at the noted point to the time of beginning after lunch and take the reading indicated by the time of ending of employment, thus quickly obtaining the total 45 wage of that employee for the day. While these readings are being taken the auditor may also take readings in column M so as to determine the time of employment before luncheon and after luncheon and the total 50 time of employment so as to make the proper entries in spaces D, E, and F.

By the use of the cards shown in Fig. 1 it

will be seen that practically a complete "production cost" record may be continuously produced for future reference, and by 55 the use of the scale shown in Fig. 2 the auditor may quickly compute the employment time and the daily wage of each employee.

We claim as our invention:

1. The combination of a time card having thereon two series of uniform spaces indicating successive and equal periods of employment, the final end of the first series and the initial end of the second series indicating several adjacent and identical periods of employment, and an integrating scale carrying a single series of uniform spaces each having the same extent as the spaces of the time card and indicating successive equal cumulated periods of employment. 60 65 70

2. The combination of a time card having thereon two series of uniform spaces indicating successive and equal periods of employment, the final end of the first series and the initial end of the second series indicating several adjacent and identical periods of employment, and an integrating scale carrying a single series of uniform spaces 75 80 each having the same extent as the spaces of the time card and indicating successive equal cumulated periods of employment, said integrating scale also carrying a plurality of columns of uniform spaces corresponding 85 to the time card spaces and carrying cumulated-wage indications.

3. A time card carrying two series of uniform spaces each space indicating a minimum employment period, and the final 90 end of one series and the initial end of the other series both indicating the same several adjacent minimum employment periods.

In witness whereof, we have hereunto set our hands and seals.
